DESIGN FOR AN ELECTRIC SHAVER CARRYING CASE

Jan Streng, Ridgefield, Conn., assignor to Remington Rand Inc., Buffalo, N. Y., a corporation of Delaware

Application February 4, 1947, Serial No. 136,668

Term of patent 14 years

(Cl. D87—3)

To all whom it may concern:

Be it known that I, Jan Streng, a citizen of the United States, resident of Ridgefield, in the county of Fairfield and State of Connecticut, have invented a new, original, and ornamental Design for an Electric Shaver Carrying Case, of which the following is a specification, reference being had to the accompanying drawing, forming part thereof.

I claim:

The ornamental design for an electric shaver carrying case, as shown.

JAN STRENG.
